UNITED STATES PATENT OFFICE.

FRANCIS R. BURGESS, OF CHICAGO, ILLINOIS, ASSIGNOR TO AMERICAN FLANGE & MANUFACTURING COMPANY, OF CHICAGO, ILLINOIS, A CORPORATION OF ILLINOIS.

CONTAINER AND SEALING MEANS THEREFOR.

Application filed March 3, 1927. Serial No. 172,376.

My invention relates to containers which are provided with bungs in the form of threaded plugs which are received within the threaded interiors of bushings that are assembled with wall portions of the containers, the invention finding particular use in connection with barrels in which oil or other liquid is packaged for shipment.

The invention has for its object the provision of means for obstructing undetectable access to and removal of the plugs. To this end I employ a sealing device assembled with a container wall and positioned to prevent undetectable access to or undetectable removal of the plug, which usually has a tool engaging formation upon its outer end, access to which is preferably obstructed by the sealing device.

In accordance with one feature of the invention, the sealing device is inclusive of a hood which preferably completely covers the otherwise exposed outer end portion of the plug so that not only is the undetectable removal of the plug guarded against but access to the tool engaging formation of the plug is guarded against and access of other dislodging tools such as chisels and punches is also guarded against. In the preferred embodiment of the invention, the sealing device is inclusive of a portion that is confined and preferably clamped in the space between the container wall and a flange that is provided upon the outer end of the bushing. The portion of the sealing device thus preferably held in place is weaved through the hood and overlies or laps its top and overlies or laps the outer end of the plug, whereby the hood is held in position and is guarded from undetectable removal. The plug is desirably also provided with a flange that clamps a gasket upon the bushing flange.

The invention will be more fully explained in connection with the accompanying drawing in which Fig. 1 is a view illustrating the preferred embodiment of the invention, the bushing and a portion of the container wall being shown in section while the plug and the sealing device that protects its outer end are shown in elevation; Fig. 2 is a view similar to Fig. 1 but showing the sealing device and plug also in section; and Fig. 3 is a sectional view on line 3-3 of Fig. 2.

The container, such as a barrel, has one

wall 1 thereof formed with a depending rim 2 which surrounds a circular hole formed through this wall. An interiorly threaded bushing 3 is snugly received within this hole and is closely surrounded by said rim, this bushing being shown with an outwardly curled inner edge portion 4 which grips the inner edge of said rim 2 and a circumscribing flange 5 which is tightly seated upon the wall 1, this flange desirablylapping this wall on the exterior of the container. The flange 5 is of hexagonal or other polygonal contour, the wall 1 being formed with a pocket receiving said flange, this pocket having a flange encompassing wall 6 which is polygonal in contour and snugly engages the perimeter of the flange to prevent the bushing from turning. The closure plug 7 is screwed within the bushing 3 and is formed with a circumscribing flange 8 which laps the flange 5 and wall 1, an annular sealing gasket 9 being desirably interposed between the flanges to render the joint between the plug and bushing fluid-tight. The outer end of the plug is formed with two tool engaging formations, one in the form of an enlargement 10 which is of hexagonal or polygonal exterior contour, and the other in the form of a recess 11 extending through the enlargement 10 and into the body of the plug, this recess being of square or other contour to receive a wrench having a plug formation snugly receivable within and corresponding in shape to said recess.

The sealing device of my invention is preferably inclusive of a plug protecting element in the form of a hood 12 which encloses the plug portions 8 and 10 and has the rim of its skirt laterally extended as indicated at 12' and resting upon the top of the pocket that receives the bushing flange 5. A guard is employed to hold the hood in place, this guard including two strip members 13 which have angular base portions 13' that receive corners of flange 5 and are received in the angular corners of the aforesaid pocket formed in the wall 1 to receive the bushing flange 5, the base portions 13' being clamped or confined between the flange 5 and wall 1 and snugly received between the perimeter of said flange and the surrounding wall of said pocket. Said guard portions 13 are thus held from shifting. They are surrounded by the rim of the

2
hood skirt and pass through the skirt to the exterior of the hood. Said guard is completed by a sealing wire 14 that laps the plug and overlies the top of the hood and is 5 so close thereto as to hold the hood in place. The wire passes through holes in the upper ends of the strips 13 and is assembled with said strips in any suitable manner as by solder, marked for identification.

10 All of the plug upon the exterior of the container is thus thoroughly guarded from undetectable access and undetectable removal by the construction described. The bushing 3 and its flange 5 surrounds the portion of the plug that is in their zone. The seal structure encloses and protects all of the plug in the outer zone adjacent the flange 5. The material of which the hood 15 is made is desirably very thin sheet metal such as tin which will readily tear or become ruptured if any attempt is made to loosen the plug as by means of wrenches applied to the plug flange 8 or the plug enlargement 20 10. Changes may be made without departing from the invention.

Having thus described my invention, I claim:

30 1. The combination with a container formed with a hole through a wall thereof; of an interiorly threaded bushing received in said hole and assembled with said wall, said bushing having a circumscribing flange 35 of polygonal contour and which laps the wall where the wall surrounds said hole, the wall being formed with angular portions receiving angular portions of said flange to prevent the bushing from turning; a closure plug 40 screwed within the bore of the bushing; and a guard lapping the plug and having a portion confined between said container wall and bushing flange in said angular wall portions and having angular portions receiving said angular portions of the flange.

45 2. The combination with a container formed with a hole through a wall thereof; of an interiorly threaded bushing received in said hole and assembled with said wall, said bushing having a circumscribing flange which laps the wall where the wall surrounds said hole; a closure plug screwed within the bore of the bushing; a hood lapping the 50 outer end of said plug to prevent undetectable access thereto; and a guard confined between said container wall and bushing flange and surrounded, adjacent said container wall, by said hood and passing 55 through the hood to the exterior thereof and across the same.

60 3. The combination with a container formed with a hole through a wall thereof; of an interiorly threaded bushing received in said hole and assembled with said wall, said

bushing having a circumscribing flange of polygonal contour and which laps the wall where the wall surrounds said hole, the wall being formed with angular portions receiving angular portions of said flange to prevent the bushing from turning; a closure plug screwed within the bore of the bushing; a hood lapping the outer end of said plug to prevent undetectable access thereto; and a guard confined between said container wall and bushing flange in said angular wall portions and having angular portions receiving said angular portions of the flange, said guard being surrounded, adjacent said container wall, by said hood and passing through the hood to the exterior thereof and across the same.

4. The combination with a container formed with a hole through a wall thereof; of an interiorly threaded bushing received in said hole and assembled with said wall, said bushing having a circumscribing flange which laps the wall where the wall surrounds said hole; a closure plug screwed within the bore of the bushing; a hood lapping the outer end of the plug; and a guard assembled with said container wall and crossing the exterior of said hood at one portion and surrounded by the hood at another portion.

5. The combination with a container formed with a hole through a wall thereof; of an interiorly threaded bushing received in said hole and assembled with said wall, said bushing having a circumscribing flange of 100 polygonal contour and which laps the wall where the wall surrounds said hole, the wall being formed with angular portions receiving angular portions of said flange to prevent the bushing from turning; a closure 105 plug screwed within the bore of the bushing; and a guard confined between said container wall and bushing flange and having angular portions received in said angular wall portions.

6. The combination with a container formed with a hole through a wall thereof; of a bushing assembled with said wall in alignment with said hole, said bushing having a circumscribing flange which laps the 115 wall where the wall surrounds said hole; a threaded closure plug screwed within the bore of the bushing; and a guard having a portion confined between said container wall and bushing flange and having a part lapping the plug, said guard and bushing flange having holding formations and said wall having a holding formation, said formation upon the wall cooperating with the other formations to prevent the guard and bushing 120 from turning.

7. The combination with a container formed with a hole through the wall thereof; of a bushing assembled with said wall in alignment with said hole, said bushing hav-

ing a circumscribing flange which laps the wall where the wall surrounds said hole; a threaded closure plug screwed within the bore of the bushing; and a guard having a portion confined between said container wall and bushing flange and having a part joined with the balance of the guard and lapping the plug, said guard and bushing flange hav-

ing holding formations and said wall having a holding formation, said formation upon the wall cooperating with the other formations to prevent the guard and bushing from turning.

In witness whereof, I hereunto subscribe by name.

FRANCIS R. BURGESS.
